UNITED STATES PATENT OFFICE.

JULES LEFÈVRE, OF PARIS, FRANCE.

LENS-CLAMPING BRACKET FOR USE WITH PINCE-NEZ GLASSES AND SPECTACLES.

Application filed June 25, 1924, Serial No. 722,230, and in France May 21, 1924.

This invention relates to lens clamping brackets for pince-nez glasses and spectacles the characteristic of which is that they are not liable to become deformed.

5 In existing pince-nez glasses and spectacles, having lens clamping brackets, it is known that after a certain period of use, the glass mounted between the arms of the bracket and bearing against its clamp, works loose with relation to the bracket, this arising from the fact that when the glass is wiped, the pince-nez or spectacle is held by the bracket, which, because of relative strains which the bracket and glass are subjected to with relation to one another, gives rise to the deformation of the clamp against which the glass no longer bears in a uniform manner, and thus interferes with the coincidence between its optical axis and the visual 20 axis of the eye.

The present invention has for its object to remedy this inconvenience by rendering the clamp of the brackets non-deformable, notwithstanding the repeated strains on the 25 glasses during wiping, by the fact that it comprises, for this purpose, a reinforcing rib which prevents the clamp from opening and thereby preventing the glass from working loose in the bracket. If necessary, two 30 or more reinforcing ribs, similar or not to one another may be provided.

In order that the invention may be clearly understood, one form of reducing the invention to practice by way of example, is hereinafter described and illustrated diagrammatically in the accompanying drawing in which:

Figure 1 is a front view of a pince-nez bracket.

40 Figure 2 is an enlarged side view of the clamp with a reinforcing rib.

Figure 3 is a horizontal sectional view along the line $\alpha-\alpha$ of Figure 2, according to which the rib projects from the clamp 45 and is solid, and

Figure 4 is a similar sectional view according to which the rib is beaten in or worked into the metal of the clamp.

In carrying the invention into effect, 1 indicates the glass bearing against the clamp 2, and fixed by a screw, between the two bracket arms 3, in the ordinary manner.

The clamp 2 bears externally and longitudinally a rib 4 which reinforces it and pre-

vents its extremities from opening, in such 55 a manner as to be always in exact engagement with the curve of the glass 1 and without becoming deformed notwithstanding the strains incurred at the time of wiping.

60 The construction of this clamp 2 with a reinforcing rib 4, could be effected either by its being produced by casting as shown in Figure 3, or by being beaten or worked as shown in Figure 4, or by being moulded, and 65 any suitable metal may be used. The rib 4 can also be provided for by autogenous soldering, or otherwise on the exterior face of the clamp 2.

70 What I claim is:

75 1. An improved non-deformable lens clamping bracket for pince-nez glasses and spectacles having spaced bracket arms between which a lens may be disposed and clamped and also having a base portion extending from the bracket arms arcuately in a direction along the edge face of the clamped lens, said base portion having a reinforcing rib extending lengthwise of the same between the ends and projecting from the base portion in a plane substantially parallel to the plane of the lens, whereby said base portion will closely fit and furnish an unyielding abutment for the clamped end of the lens.

80 2. A lens mounting comprising an element having flanges extending along and engaging an edge of the lens and having clamping ears embracing and anchored to a portion of the lens, the flanges being formed of relatively thin material and having a reinforcing rib extending substantially in the plane of the lens and in a direction along the edge of the lens.

85 3. A lens mounting comprising a body portion having clamping ears embracing a portion of the lens and having flanged portions extending along and contacting with an edge of the clamped lens, said body portion and flanges being formed of thin material and having a portion along the edge of the lens doubled away from said lens edge to form a reinforcing rib extending along the flanges to prevent their flexure.

100 105 In witness whereof I hereunto subscribe my signature.

JULES LEFÈVRE.
